Primary Examiner — Brett Miller*Assistant Examiner* — Jessica M Gebhart(74) *Attorney, Agent, or Firm* — Bruce S. Shapiro(57) **CLAIM**

The ornamental design for a small container, as shown and described.

DESCRIPTION

FIG. 1 is a frontal-side perspective view of a small container;

FIG. 2 is a front view thereof;

FIG. 3 is a top view thereof;

FIG. 4 is a bottom view thereof;

FIG. 5 is a right side view thereof;

FIG. 6 is a left side view thereof; and,

FIG. 7 is a rear view thereof.

The broken lines illustrate portions of the small container and form no part of the claimed design.

1 Claim, 7 Drawing Sheets(56)
